UNITED STATES PATENT OFFICE.

CHARLES S. MCKENNEY, OF PETERSBURG, VIRGINIA, ASSIGNOR TO SEWARD TRUNK AND BAG COMPANY, OF PETERSBURG, VIRGINIA, A CORPORATION OF VIRGINIA.

DESIGN FOR A TABORET OR ARTICLE OF SIMILAR NATURE.

Application filed February 4, 1926. Serial No. 16,397. Term of patent 14 years.

To all whom it may concern:

Be it known that I, CHARLES S. MCKENNEY, a citizen of the United States, residing at Petersburg, in the county of Dinwiddie and State of Virginia, have invented a new, original, and ornamental Design for a Taboret or Article of Similar Nature, of which the following is a specification, reference being had to the accompanying drawing, forming part thereof.

The figure is a perspective view of a taboret or article of similar nature, showing my new design.

I claim:

The ornamental design for a taboret or article of similar nature as shown.

CHAS. S. MCKENNEY.
